UNITED STATES PATENT OFFICE.

JUSTIN LEBOVICI, OF OAKLEY, OHIO, ASSIGNOR TO THE TRIUMPH ELECTRIC COMPANY, A CORPORATION OF OHIO.

INTERLOCK CIRCUIT PROTECTOR.

1,422,110.

Specification of Letters Patent. Patented July 11, 1922.

Application filed April 26, 1919. Serial No. 292,976.

To all whom it may concern:

Be it known that I, JUSTIN LEBOVICI, a citizen of the United States, residing at Oakley, in the county of Hamilton and State 5 of Ohio, have invented certain new and useful Improvements in Interlock Circuit Protectors, of which the following is a specification.

This invention relates to overload circuit 10 protectors and particularly to such protectors for use where a plurality of circuits or lines are to be simultaneously broken by an overload in any one of their number.

In polyphase circuits including a poly- 15 phase induction motor, for instance, the blowing of a fuse in one phase is a decided menace to the connected apparatus if the other lines are not simultaneously opened; for it leaves the motor thrown across two 20 lines in which condition it will burn out unless a fuse or other circuit breaker of a second phase acts in time to prevent it.

The object of this invention is to provide 25 a circuit protector combining with two or more lines or circuits whereby the lines are so related that an overload breaking the circuit in one line with automatically and simultaneously interrupt other lines and disconnect the load. A further object of the 30 invention is to make this interrupting action sure and instantaneous by normally maintaining circuit opening forces in one line balanced against operation by a circuit breaking element of another line so that 35 overload actuation of the latter will break the circuits of both lines.

In the accompanying drawings,

Fig. 1 is a vertical section through one embodiment of the invention.

Fig. 2 is a side elevation of the same,

Fig. 3 is a diagram illustrating one embodiment of this invention applied to a polyphase circuit, and

Fig. 4 is a view similar to Fig. 3 illustrating a modification.

In the embodiment of the invention illustrated in Figs. 1 and 2 a fuse box 5 is provided with terminals 6 and 7 for one line and terminals 8 and 9 for another line which 50 is to be broken simultaneously with the first line in case the first line is overloaded. The first line circuit passes through terminals 6 and 7, flexible conductors 10 and 11, fuse blocks 12 and 13, and fuse 15 fastened be-

tween said blocks. The blocks 12 and 13 are 55 pivotally mounted in the casing 5 at 16 and 17 respectively and resiliently pressed apart by springs 18 and 19 so that when the connecting fuse 15 melts or blows the blocks 12 and 13 will move apart. Fuse blocks 12 60 and 13 are insulated from their pivoted supporting blocks.

When the blocks 12 and 13 are held together by fuse 15 the inclined surfaces 20, 21 of the blocks serve to press the switch 65 bar 23 to the left (Fig. 1) to hold its leaf spring switch 24 across contacts 25 and 26 of the terminals 8 and 9 to close the circuit of the second line. The switch 23, 24 is guided on the fiber tube 27 supported on the 70 bolt 28 and is pressed open away from the contacts 25, 26 by coil spring 29 between the switch 24 and the side of the box 5. The front of box 5 is open and is provided with a transparent cover 30 and cover retaining 75 rim 31. Should the fusible element 15 break the circuit through terminals 6, 7, springs 18 and 19 will spread fuse blocks 12 and 13 permitting the spring 29 to open switch 24 and break the circuit between terminals 8 and 9. When the cause of the overload 80 has been remedied the apparatus is reassembled in protective position by removing cover 30, closing switch 24 fastening a new fuse 15 between blocks 12, 13, as by screws 85 32, and replacing the cover 30 and its retaining rim 31.

The application of this invention to a three-phase induction motor circuit is illustrated in diagram in Fig. 3, in connection 90 with a modified form of protector, where the primary windings of the phases, A, B, C, are connected through fuses F¹, F², F³, to supply lines a, b, c, each line circuit including a gap G¹, G², G³ controlled by one of the 95 other fuses, the rotor secondary of the motor being indicated at R. Upon any of the circuit openers or fuses F¹, F², F³ being overloaded so as to break the respective circuit, a spring S¹, S² or S³ will raise the corresponding fuse block L¹, L² or L³ and with it the switch T¹, T² or T³ to break the gap G¹, G² or G³ of another phase circuit and thus two phases of three being open the motor is operatively and safely disconnected 100 105 110 from the line.

In Fig. 4 a circuit protector showing one embodiment of this invention is illustrated

in connection with a polyphase circuit and with a switch having a no voltage release. In this system each phase primary A, B, C is connected to its corresponding line a , b , 5 c , through a fuse F^1 , F^2 , F^3 and the circuit in series with a suitable source of current X and the no voltage release V passes through gaps G^{11} , G^{12} , G^{13} so that when any one of the fuses F^1 , F^2 , F^3 blows, the spring S^1 , S^2 10 or S^3 will open the corresponding gap G^{11} , G^{12} or G^{13} and this in turn will act upon the no voltage release V which will drop its core on arm m to turn shaft h to tip up arms n_1 , n_2 , n_3 and permit the toggles below switches W_1 , W_2 , W_3 to collapse and trip open all the switches simultaneously 15 and disconnect the motor lines A, B and C from the supply lines.

In the embodiments of this invention 20 shown and described the interlocking circuit is held closed by tension on the circuit breaking element of the overload circuit and the pressure of the parts continually tends to open both circuits, the breaking of the 25 overload and interlocking circuits is made certain at any excess load and practically simultaneous so as to prevent the blowing of a second fuse and both the circuits are maintained open until intentionally closed. 30 In the embodiments shown the protector of this invention is simple in structure, sure in operation, and easily wired into a variety of combinations of circuits. The invention may be applied to single phase and direct 35 current systems to open both sides of the line simultaneously and it is obvious that electromagnetic or other forms of circuit breaking elements may be used in place of the fuses shown and described.

40 I claim:

1. The combination with a polyphase circuit of means for breaking the circuit of one phase by the breaking of a circuit of another phase comprising an independently openable circuit breaker element in the circuit 45 respectively of each phase adapted to be controlled by a predetermined current in its circuit, a second circuit breaking element respectively in the circuit of each phase re- 50 silently pressed in a direction to open the circuit of its respective phase, and each of said second circuit breaking elements being openable independently of each other, and means whereby the opening pressure on each 55 of said second circuit breaking elements is respectively transmitted to one of said first circuit breaking elements connected in a different phase.

2. The combination with a polyphase circuit 60 of a circuit breaking element in the circuit of each of said phases respectively and each of said elements being openable independently of each other, a second circuit breaking element in the circuit of each of 65 said phases respectively, and openable inde-

pendently of each other, the first named elements of each phase being in series respectively with the second named elements of each phase, and means for causing the opening of one of said second named elements 70 upon the opening of one of said first named elements in a different phase.

3. The combination with a polyphase circuit of a circuit breaking element in the circuit of each of said phases respectively and openable independently of each other, a second circuit breaking element in the circuit of each of said phases respectively and openable independently of each other, each of said second circuit breaker elements being 80 biased to move to open position, and means whereby each of said second circuit breaking elements is held in closed position respectively by one of said first named circuit breaking elements connected in a different 85 phase of the circuit.

4. The combination with a polyphase circuit of a circuit breaking element in the circuit of each of said phases respectively and openable independently of each other upon the passage of an overload current, a second circuit breaking element in the circuit of each of said phases respectively and openable independently of each other, each of said second circuit breaker elements being 90 biased to move to open position, and means whereby each of said second circuit breaking elements is held in closed position respectively by one of said first named circuit breaking elements connected in a different 95 phase of the circuit.

5. The combination with a polyphase circuit of a circuit protector adapted to open the circuit of one phase by a predetermined current in the circuit of another phase, comprising oppositely movable fuse blocks, a fuse holding said blocks together, a switch member retained in one position by said blocks in held position, and means for moving said switch member on melting of said 100 fuse.

6. The combination with a circuit protector adapted to open the circuit of one phase by a predetermined current in the circuit of another phase comprising a pair of 105 fuse blocks yieldably forced apart, a fuse holding said blocks toward each other, a switch member retained in closed position by said blocks in held position, and means moving said switch member and said blocks to open said blocks and switch member upon melting of said fuse.

7. The combination with a polyphase circuit of a fuse in the circuit of each of said phases respectively, a circuit breaking element in the circuit of each of said phases respectively and openable independently of each other, said circuit breaking elements being biased to move to open position, and means whereby the fuse of each circuit re- 115 120 125 130

spectively holds in closed position one of said circuit breaking elements connected in the phase of another circuit.

8. The combination with a polyphase circuit of a fuse in the circuit of each of said phases respectively, a circuit breaking element in the circuit of each of said phases and in series with said fuses respectively and openable independently of each other, 5 said circuit breaking elements being biased to move to open position, and means whereby the fuse of each circuit respectively holds

in closed position one of said circuit breaking elements connected in the phase of another circuit.

15

9. In a circuit protector adapted to open one circuit by a predetermined current in another circuit, the combination with pivoted fuse blocks having inclined surfaces, a switch member in one circuit engaging said 20 surfaces to press said fuse blocks apart, and a fuse in another circuit holding said blocks against separation.

JUSTIN LEBOVICI.
